BRAKE MECHANISM FOR MECHANICALLY
MOVABLE SHELVES

William Doggett, New York, N. Y.

Application May 4, 1935, Serial No. 19,773
Renewed January 14, 1939

1 Claim. (Cl. 188—171)

This invention relates to new and useful improvements in a brake mechanism for automatically movable shelves.

The invention has for an object the construction of a brake mechanism for controlling the movements of movable shelves or a similar article which is confined to moving within a specified course.

A further object of the invention is the provision of an electric solenoid connected in series with the motor for moving the shelves which will release the brake mechanism when the motor operates.

Still further the invention contemplates an arrangement for manually releasing the brake mechanism so that the shelves may be manually moved.

Another object of the invention is the construction of a device as described which is simple and durable and which can be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

30 Fig. 1 is a front elevational view of an automatically movable shelf unit according to this invention.

Fig. 2 is a sectional view taken on the line 2—2 of Fig. 1.

35 Fig. 3 is a fragmentary enlarged longitudinal sectional view of a portion of Fig. 2, illustrating the particular details within the transmission housing of the electric motor.

Fig. 4 is a sectional view taken on the line 4—4 of Fig. 3, with schematic wiring applied.

40 Fig. 5 is a front elevational view of another form of the invention, a portion thereof being illustrated in section to show interior parts.

Fig. 6 is an enlarged detail view of a portion of Fig. 4.

45 The brake mechanism for automatically movable shelves, according to this invention, includes a stationary frame 10 in which a shelf unit 11 is slidably mounted. A means is provided for moving the shelf unit and includes an electric motor 12. More particularly, the motor 12 drives a pinion 13 meshing with a stationary rack 14 mounted upon the wall 15. The motor 12 is mounted upon the top of the shelf unit 11. The arrangement is such that when the motor 12

drives the pinion 13 in one direction, the shelf unit is moved up, and when the rotation is in the opposite direction, the shelf unit is moved down.

The frame 10 consists of a top portion 10^a connected with side portions 10^b. The frame is open at the front and bottom and is adapted to encase the sides and the top of the shelf unit. The shelf unit 11 comprises a box-like structure 11^a open at the front and provided with several shelves 11^b. The sliding mounting of the shelf unit is accomplished by several rollers 16 mounted upon the sides of the box structure 11^a and engaging in tracks 17 stationarily fixed upon the wall 15. The shelf unit is counterbalanced so that it is adapted to move more readily. A cable 18 is attached to the top of the shelf unit and extends over several rollers 19 and into a wall cavity 15^a. A counterweight 20 is attached to the free end of the cable. 20

The electric motor 12 has its driving shaft indicated by reference numeral 12^a. A pinion 22 is fixed upon the end of the shaft 12^a and connects with a speed reducing unit within a housing 23 which is fixedly mounted upon the side 25 of the casing of the motor 12. This reduction unit comprises several spindles and meshing gears and terminates in a shaft 13^a. 25

The pinion 13 is mounted on the extended end of the shaft 13^a. 30

A brake is associated with the transmission reduction unit within the casing 23 for the purpose of holding the pinion shaft 13^a from turning due to the counterweight 20 or the weight of the shelf unit so that the shelf unit maintains a 35 fixed position. This brake comprises a brake band 25 fixed at one end on a bracket 26 mounted on the interior wall of the casing 23. The brake band encircles a wheel which is fixed upon a spindle of the transmission. This wheel 27 40 is formed with peripheral teeth 27.

The brake band 25 has a bottom area 25' formed with teeth adapted to coact with the teeth 27' to hold the spindle against rotation. The free end of the brake band 25 connects with 45 the plunger 28 of a solenoid 29. A spring 30 is associated with the plunger 28 and a stationary part for normally urging the brake band 25 into the operative condition, that is, the condition in which the teeth 25' engage the teeth 27'. 50 The solenoid 29 is connected in series with the electric motor 12 which is controlled by a switch 31. The electric circuit is indicated by reference numeral 32. This circuit connects the switch 31, the solenoid 29, and the motor 12 in 55

series. In Fig. 4 the motor is schematically indicated by a circle 12, a pair of tangential leads 12^b, and field 12^c.

A conduit 33 extends from the casing 23 to a point 33' (see Fig. 2) located at the bottom of the shelf unit. A cable 34 is attached to the lower end of the plunger 28 and slidably extends through the conduit 33 and over rollers 35 mounted on the bottom of the shelf unit and terminates in a finger ring 36.

The finger ring 36 may be pulled to manually move the plunger 28 against the action of the spring 30 to release the brake so that the shelf unit may be manually moved. When the switch 31 is closed, the solenoid 29 will electrically move the core 28 to release the brake, and simultaneously the motor will be energized so that the shelf unit is free to move and moves in one direction. A reversing switch 31' is provided to reverse the motor so that the shelf unit may be electrically moved in the other direction.

In Fig. 5 another embodiment of the invention has been disclosed in which a shelf unit 11' is illustrated provided with rollers 16 by which it is slidably supported upon tracks 17'. A counterweight is associated with the shelf unit and consists of a cable 18' connected with the shelf unit and extending over a pulley 19' and supporting a counterweight 20'. This shelf unit is raised or lowered by a cable 38 which is attached on one end 38' upon the top of the shelf unit 11' and extends over rollers 39 and is attached at the other end and wound upon a drum 40. This drum is rotatively supported and is equipped with a gear 41 meshing with the pinion 13 of the motor 12. This motor is provided with the trans-

mission casing 23 with the mechanism previously described, within said casing. A conduit 33' extends from the casing 23 and the control cable 34 extends through this conduit terminating in the ring 36.

The shelf unit may be electrically moved up or down by controlling the switches (31 and 31'). The shelf unit may be manually moved by pulling the ring 36 so as to draw the cable and release the brake holding the motor.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:

In a device of the class described, a brake drum on a rotative shaft connected with a source of power for controlling the motion of a movable member, a brake shoe engaging around said brake drum and having one of its ends fixedly mounted and its other end free, a solenoid having its core connected at one end to the free end of said brake shoe, an electric circuit for energizing said solenoid to move said core to release said brake shoe and permit said drum to rotate, and a cable connected to the other end of said core by which said brake shoe may be manually released independent of said circuit permitting a manual movement of said movable member.

WILLIAM DOGGETT.
